UNITED STATES PATENT OFFICE

EDWARD W. CARPENTER, OF FAIRFIELD, CONNECTICUT, ASSIGNOR TO THE E. W. CARPENTER MANUFACTURING COMPANY, OF BRIDGEPORT, CONNECTICUT, A CORPORATION OF CONNECTICUT

KNIFE SHARPENER

Application filed November 8, 1930. Serial No. 494,306.

This invention relates to new and useful improvements in blade sharpeners of the type employing two series of hardened steel discs, the discs of each series being spaced apart and the discs of one series being opposite the spaces between the discs of the other series and the discs of one series overlapping the discs of the other series.

An object of the invention is to provide an improved mounting frame or housing for blade sharpeners of the type described the improved housing being formed of a single blank of sheet metal and including side walls on and between which the sharpening discs are arranged, the housing also including feet for resting on a supporting surface and substantially enclosing the discs but being cut away to provide an entrance for the blade to be sharpened and further including integral resilient extensions to be received in a handle.

It is also an object to provide a housing or mounting of the character described and which shall be neat and of good appearance and which may be manufactured and sold at a relatively low cost.

Other objects and advantages will become apparent from a consideration of the following description taken in connection with the accompanying drawing wherein a satisfactory embodiment of the invention is shown. However, it will be understood that the drawing and description are for the purpose of disclosure only and that the invention comprehends all such changes and modifications as fall within the scope of the appended claims.

In the drawing:

Fig. 1 is a side elevational view of the improved sharpener;

Fig. 2 is a top plan view of the same, a portion of the handle being shown in section;

Fig. 3 is a bottom plan view of the sharpener with the handle removed; and

Fig. 4 is an end elevational view with the handle removed, one of the legs being sectioned.

Referring in detail to the drawing the sharpener as shown includes a housing 5,

within which is disposed the series 6 and 7 of hardened sharpening discs, the discs of the respective series being spaced as by washers 8 and the discs of the series 6 being arranged opposite the spaces between the discs 7 and 55 vice versa and the discs overlapping as shown. The sharpener is adapted to be moved about and held by a handle 9, connected to the housing or mounting frame 5 as will later be described in detail.

The housing 5 is formed from a single piece of sheet metal bent upon itself whereby it is of substantially inverted U-shape in transverse cross section including a connecting portion 10 and side walls or portions 11 55 and 12. Extending between and supported by the walls 11 and 12 are spaced pins or rivets 13 on which are rotatably supported the spaced discs 6 and 7 and the washers 8 previously referred to.

Intermediate the ends of the housing 5 the connecting portion 10 and the side walls 11 and 12 are cut away as at 14 to provide an entrance for the blade to be sharpened whereby it may be introduced into the channel 15 to be operated and sharpened by drawing it across the discs in a manner well known. At their lower edges the side walls 11 and 12 flare outwardly as at 16 and 17 and are cut away as at 18.

The vertical edges of the outwardly flared portions 16 and 17 carry extensions or lugs 19 bent to extend toward each other as shown whereby to give the housing a neat and finished appearance. Further, the lower edges 85 of the portions 16 and 17, at the extremes of the cutaway portions 18 carry lugs or extensions 20 inturned as shown and providing feet for supporting the sharpener.

These feet 20 are disposed below the lower edges of the extensions 19 to provide flat surfaces for engaging supporting surfaces whereby the likelihood of scratching or otherwise marring the supporting surface is obviated. Also, it will be seen that the side walls of the housing are supported above any table or the like on which the sharpener may be rested. This is, of course, due to the fact that the side walls are cut away as at 18.

Carried by corresponding edges of the

walls 11 and 12 above the flared portions 16 and 17 are a pair of extensions 21 and 22 bent toward each other and abutting as at 23. These extensions 21 and 22, from the point 5 23 are designated 21_a and 22_a and are transversely curved as shown and tend to spring apart as most clearly shown in Figs. 3 and 4. The portions 21_a and 22_a are adapted to be received in a socket 24 in the handle 9. To 10 accomplish this the portions 21_a and 22_a must be sprung together and when received in the socket 24 tend to spring apart and thereby frictionally secure the handle to the housing. A ferrule 25 may be provided on the end of 15 the handle to keep it from splitting. From the foregoing it will be seen that the housing or frame 5 is formed in one piece stamped and shaped as shown. Further, a housing of neat appearance is provided since the extensions 19 conceal the feet 20 and give a finished product. Additionally, the extensions 21 and 22 extending toward each other close 20 the space between the rear edges of the vertical portions of the sides or walls 11 and 12. 25 The housing being stamped and bent may be manufactured at a comparatively low cost. Since the extensions 21_a and 22_a, for securing the handle 9 to the housing, are formed with the housing, no additional expense is 30 involved in providing means for attaching the handle. It will also be appreciated after an inspection of the drawing that the discs 6 and 7 are substantially enclosed and the handle 9 being remote from the entrance 14 for 35 the blade to be sharpened there is little chance of the operator becoming injured. Also, the flared or outwardly and downwardly inclined portions 16 and 17 of the housing give the latter a relatively wide base whereby the 40 same is not likely to tilt or wobble while in use.

Having thus set forth the nature of my invention, what I claim is:

1. In a sharpener of the class described including overlapping sharpening discs, a housing, said housing being substantially inverted U-shape in transverse section, said sharpening discs supported within the housing, the side walls of the housing each outwardly flared at its lower portion, the said flared portions having the central portion of their lower edges cut away, and said flared portions at their lower edges at each end of their cutaway portion carrying extension 45 turned under the housing and having their

lower surfaces disposed below the lower edges of the housing whereby to provide relatively broad supporting feet for the housing.

2. In a sharpener of the class described including overlapping sharpening discs, a 70 housing, said housing being substantially inverted U-shape in transverse section, said sharpening discs supported within the housing, the side walls of the housing each outwardly flared at its lower portion, an extension on each vertical edge of said flared portions, said extensions on the corresponding edges of the flared portions disposed toward each other and each partially closing the space between said side walls, the said flared 75 portions having the central portion of their lower edges cut away, and said flared portions at their lower edges at each end of their cutaway portion carrying extensions turned under the housing and having their 80 lower surfaces disposed below the lower edges of the housing whereby to provide relatively broad supporting feet for the housing.

3. In a sharpener of the class described including two overlapping series of sharpening 90 discs, a housing, said housing being substantially inverted U-shape in cross section, said discs disposed between and supported by the side walls of the housing, said housing cutaway to provide an entrance to the sharpening discs for the blade to be sharpened, extensions on corresponding edges of said side walls, said extensions bent toward each other across one end of said housing and then tending away from one another, a handle having 100 a socket, and said extensions adapted to be sprung toward each other and insert into the socket whereby the handle is attached to the housing.

4. In a sharpener of the class described including two overlapping series of sharpening discs, a housing of resilient sheet metal and substantially of inverted U-shape in cross section, means mounting the discs in the housing, said housing having an opening in its top wall providing an entrance for the blade to be sharpened, the lower free edges of the side walls forming feet to support the device, an integral extension on one upright edge of each side wall and normally tending to separate at their free ends, and a handle having a socket, said extensions being inserted in said socket and holding the handle thereto by their resilient action.

EDWARD W. CARPENTER.
